DISK ROLLING MACHINE

Luther T. Pedigo, Greensburg, Kans.

Application April 25, 1935, Serial No. 18,252

11 Claims. (Cl. 76—89.2)

This invention relates to a disk rolling machine, and more particularly to a machine by use of which marginal edge portions of disks such as used upon plows and harrows may be 5 rolled when dull in order to restore a sharp edge which will easily penetrate the ground when a plow or harrow is in use.

One object of the invention is to provide a machine of this character by means of which a 10 rolling action under pressure may be applied circumferentially of a disk about the marginal edge thereof and cause a dulled disk to have its marginal portion tapered toward its edge and thus sharpened without heating the disk which would 15 spoil its temper and without cutting the disk through the medium of a file, grindstone, or other abrading element.

Another object of the invention is to so construct the machine that one of the rollers between which marginal portions of a disk moves 20 may be forced toward the companion roller by hydraulic pressure set up by a manually operated device which is easy to actuate and thus provide a manually operated machine which may be very 25 easily operated by one person.

Another object of the invention is to so construct the means for applying hydraulic pressure that the pressure applied may be accurately controlled and very easily increased or reduced 30 when necessary and thus permit pressure to be gradually increased during a rolling operation and easily and quickly released when a sharpening operation has been completed.

Another object of the invention is to provide 35 improved means for rotatably supporting a disk to be sharpened and so construct and mount the roller supporting means that a disk carried thereby may be disposed at a desired angle relative to the rollers and shifted toward and away from 40 the rollers during a sharpening operation.

Another object of the invention is to provide 45 a machine of this character which will be compact in construction and very strong and durable.

The invention is illustrated in the accompanying 45 drawings, wherein

Figure 1 is a perspective view of the improved disk rolling machine.

Figure 2 is a section taken vertically through the machine adjacent one end thereof.

Figure 3 is a sectional view taken vertically 50 through the machine in the plane of the roller carrying shafts.

Figure 4 is a sectional view taken horizontally 55 through the machine along the line 4—4 of Figure 2.

Figure 5 is a fragmentary view taken along the line 5—5 of Figure 3 and illustrating the manner of constructing and mounting the bearing blocks for the roller carrying shafts.

Figure 6 is an enlarged fragmentary sectional view taken vertically through a corner post in which the pump for exerting hydraulic pressure is mounted.

Figure 7 is a section taken along the line 7—7 of Figure 3.

Figure 8 is a section taken along the line 8—8 of Figure 7.

Figure 9 is a section taken along the line 9—9 of Figure 8.

Figure 10 is a fragmentary view showing in 15 bottom plan one of the supporting legs and a corner portion of the frame.

This improved disk rolling machine has a frame including a lower plate or base 1 and an upper plate or top 2, the corner portions of which 20 are formed with openings through which are passed the reduced and threaded upper and lower end portions of the corner posts or standards 3 and 4, and referring to Figure 2 it will be seen that lower end portions of the corner posts carry 25 sleeves or collars 5 against which the bottom plate is secured by nuts 6 which also serve to firmly secure feet 7 about the posts against the under face of the bottom plate. These feet or legs extend downwardly at an outward incline from 30 the bottom plate and are formed with openings 8 through which bolts may pass in order to firmly but detachably secure the machine upon a foundation.

The upper plate 2 is also secured upon the corner posts or standards by nuts 9, and referring 35 to Figures 1 and 2 it will be seen that upper sleeves 10 are provided about the standards 3 to engage the under face of the top plate 2, whereas the posts or standards 4 are formed near their upper ends with shoulders 11 upon which the upper 40 plate rests. Before the nuts of the standards 4 are applied, a head block or cross beam 12 is set in place upon the upper plate and, therefore, the nuts carried by upper ends of the posts 4 will serve to hold the head block in place, as well as the 45 upper plate. All of the corner posts or standards have been shown in the form of tubes. This not only reduces the weight of the machine, but also adds to its strength and permits one of the posts 4 to be plugged at its upper and lower ends, as 50 shown at 13 and 14, and serve as a container or reservoir for oil or any other liquid forming a portion of the hydraulic pressure applying mechanism to be hereinafter described.

Bearing blocks 15 and 16 extend transversely 55

of the frame between companion standards 3 and 4 and are arranged in pairs, as shown clearly in Figures 1 and 5. Referring particularly to Figure 5 it will be seen that each bearing block has 5 arcuate shoes 17 at its ends which extend partially about the standards 4 and, therefore, serve to hold the bearing blocks in place between the companion standards but permit the bearing blocks to be slid into and out of place. It will also 10 be noted that this manner of mounting the bearing blocks permits the blocks extending between the standards 4 to be forced downwardly when pressure is applied to sharpen a disk, as will be hereinafter fully set forth. The bearing blocks 15 terminate in spaced relation to the upper plate and the bearing blocks between the standards 3 are overlapped by the sleeves 10 so that these blocks will be firmly held against vertical movement when the machine is assembled. Abutting 20 faces of the bearing blocks have their intermediate portions formed with recesses 18 which cooperate to form a pocket 19 in which bushings 20 are mounted and held against rotation by the flat faces of the pockets and the bushings. 25 Through these bushings are rotatably mounted upper and lower shafts 21 and 22 carrying gears 23 by means of which rotary motion is transmitted from one shaft to the other. Outer end portions of the shafts project from the bearing 30 blocks carried by the standards 4 and upon these projecting end portions of the shafts are mounted rollers 24 which are formed of very hard metal and secured by nuts 25, it being understood that the rollers will be firmly fixed to the shafts in any 35 desired manner so that they will rotate with the shafts.

The two shafts 21 and 22 are to be rotated during operation of the machine and in order to do so there has been provided a drive shaft 26 which 40 is rotatably mounted in bearings 27 bolted to the upper plate 2. This drive shaft projects from the frame at the opposite side thereof from the rollers 24 and carries a pulley 28 about which a belt 29 engages so that rotary motion may be imparted 45 to the drive shaft from a motor or other source of power. A gear housing 30 formed of separable sections is secured vertically against the frame with the shaft 26 extending through the upper portion of the gear housing and an end portion 50 of the shaft 22 extending into its lower portion, as clearly shown in Figure 3. Sprockets 31 and 32 are carried by the portions of the shafts 26 and 22 within the gear housing or shield and about these sprockets is trained a sprocket chain or 55 toothed belt 33 by means of which rotary motion is transmitted from the shaft 26 to the shaft 22. The shield or housing 30 entirely encloses the two sprockets and the sprocket chain or toothed belt thus preventing danger of the belt or chain slipping off of the sprockets and also eliminating 60 danger of a person being injured by contact with the sprocket chain or by being struck by the chain or belt if it should break.

A disk which is to be sharpened is to be rotatably supported at a side of the frame in operative relation to the rollers 24 and angularly adjusted in order to dispose it in proper angular relation to the rollers. The means for supporting a disk includes a bracket 34 having a solid shank 35 which is slidably mounted in bearings 36 and 37 bolted to the lower plate 1. The bearing 37 has upstanding ears 38 through which a bolt 39 passes and upon the bolt is mounted a disk 40 which fits into a groove 41 formed longitudinally in the 75 shank of the bracket. By this arrangement, the

bracket may be slid longitudinally to dispose a disk in proper spaced relation to the side of the frame and when the bolts are tightened to secure the bracket in a set position, the disk 40 will prevent turning of the shank in the bearings 36 and 37 and the disk being sharpened will be prevented from moving out of an angularly adjusted position. At its outer end, the shank 34 carries a head 42 having clamping jaws 43, through the free ends of which is passed a bolt 44 in order that the jaws may be drawn into gripping engagement with the shank 45 of a companion clamp 46. This clamp 46 extends transversely of the bearing bracket 34, and between the jaws 47 of the clamp 46 extends the shank 48 of a plate or 10 platform 49. By loosening the bolt 50, the table 49 may be vertically adjusted and the bolt retightened to secure it in the adjusted position, and by loosening the bolt 44 the table may be shifted to an angularly adjusted position and then secured 20 by retightening the bolt. It will thus be seen that the platform or table 49 may be adjusted for height and distance away from the rollers 24 and may also be angularly adjusted in order that a disk to be sharpened may have its marginal portion 25 properly engaged between the rollers.

The disk 51, which is to be sharpened, is disposed about a post or axle 52 where it rests upon wheels 53 rotatably connected with arms 54 which radiate from a hub 55, the arms and hub being 30 formed integral with a circular disk or plate 56 resting upon the shelf or table 49 where it is secured by bolts 57 and 58. The hub 55 is hollowed from its under face to form a pocket or bearing in which is disposed the circular foot 59 at the lower end of the post 52 and this foot has its upper face formed with an annular race to receive bearing balls 60 and thus permit the post to rotate freely relative to the plate 56. After the disk 51 has been set in place with its concaved 40 face resting upon the wheel 53, a tapered block 61 is passed downwardly about the post through the center opening of the disk until it has tight wedging engagement with the disk and a tapered retainer or key 62 is driven through a slot 63 45 formed transversely of the post to firmly hold the block in place. A cotterpin or equivalent removable fastener is then passed through one of the openings 63 of the key 62 to hold this key in place. It will thus be seen that the disk 51 and 50 the post 52 will rotate as a unit with the disk resting upon the wheels 53 and rotation of the post being adjusted by the bearing balls 60. It is desired to permit the disk 51 to be shifted toward and away from the rollers 24 during a sharpening 55 operation and, therefore, the plate 56 has been provided with a handle 64 which extends radially therefrom and at its inner end is formed with a foot 65 which rests upon the plate 56 and is secured thereon by a screw 66 and by the bolt 57. 60 This bolt 57 passes through a slot 67 which is arcuate, as shown in Figure 9, and referring particularly to Figure 7 it will be seen that the slot 67 is concentric to the opening through which the bolt 58 passes but eccentric to the shank 48. 65 Therefore, by loosening the bolt 57 and grasping the handle 64, the plate 56 may be swung about the bolt 58 as a pivot to shift the disk 51 toward or away from the rollers 24 and the bolt 57 then again tightened to hold the plate 56 and post 52 70 in an adjusted position.

When this machine is in operation, the disk to be sharpened is applied to the post 52 and proper adjustments made to dispose the marginal portion of the disk between the rollers 24. The shafts 21 75

and 22 are rotated from the drive shaft 26 and as the rollers 24 rotate, the disk 51 will rotate, together with the post 52. Pressure must be applied in order to roll the marginal portion of the disk 51 and sharpen the same. In order to do so, there has been provided a cup 68 which rests from the upper bearing block 15 intermediate the length of the cross beam or head block 12 and this cup or cylinder slidably receives a block or piston 69 which is provided with sealing rings 70 to insure a close fit. A passage 71 is bored through the center of the piston 69 and continued upwardly through the upper plate 2 and cross beam 12 to receive the threaded shank or neck of a gage 72 by means of which pressure exerted is to be determined. A side passage 73 leads from the passage 71 to the inner side face of the cross beam or head block and in this side passage is engaged one end of a pipe 74, the other end of which is connected with a pipe 75 extending vertically of the frame with its lower end portion passing through an opening formed in the base plate 1. A branch 76 controlled by a valve 77 extends from the upper end of the pipe 75 and is threaded into an opening formed in a side of the adjacent corner post or pillar 4 so that oil or other liquid may flow through this branch pipe and into the interior of the pillar which constitutes a reservoir for the liquid. At its lower end, the pipe 75 is extended toward the lower end of the pillar, as shown at 78, and terminates in an elbow 79 which is screwed into the lower end of the plug 14. Referring to Figure 6 it will be seen that the plug 14 is formed with a center bore into which the elbow 79 is screwed and that this bore is extended upwardly through a plunger or piston 80 about which is slidably engaged a cylinder 81 having a hollow shaft 82, the upper end of which is screwed into a socket 83 at the lower end of a pump rod or dasher 84. A valve ball 85 for yieldably closing the reduced inlet opening 86 and the upper end of the bore of the plug and piston is yieldably held closed by a spring 87, the lower end of which bears against the elbow 79. Therefore, liquid may be forced past the valve 85 and upwardly through the pipe 75, but the liquid will be prevented from returning to the reservoir through the opening 86. A hollow seat 88 is threaded into the lower end of the shank 82 and constitutes a support for the lower end of a spring 89 which holds a valve ball 90 in closing relation to an inlet 91 which extends upwardly from the upper end of the chamber 92 formed in the hollow shaft and has side ports 93 which open through side portions of the shank a short distance below the upper end thereof. The upper end portion of the pump rod 84 slides through the bushing 13 which forms a tight joint about the pump rod and at its upper end the pump rod is forked, as shown at 94, and pivoted to an operating handle or lever 95 which extends longitudinally of the cross beam 12 and at one end is pivoted to a fulcrum 96 carried by an end of the cross beam which projects from the top plate 2 of the frame.

By swinging the lever upwardly to raise the pump rod, the cylinder 81 will be drawn upwardly and as this cylinder is drawn upwardly, oil will be sucked through the inlet 91 to fill the chamber 92 and interior of the cylinder. Pressure will then be exerted to force the lever downwardly, and during this movement, the cylinder will move downwardly above the piston or plunger 80 and oil in the cylinder will be forced past the valve ball 85 into the bore of the piston and upwardly through the pipe 75. The valve 77 will be closed

and, therefore, when the oil or other liquid reaches the upper end of the pipe 75 it will pass through the pipe 74 and passages 73 and 71 into the bottom of the cylinder 68 where it will act against the under face of the piston 69 and exert pressure which will force the bearing blocks carried by the standards or columns 4 downwardly. Therefore, the shaft 21 carrying the upper roller 24 will be forced toward the lower roller and pressure will be applied to the marginal portion of the disk 51 which is engaged between these rollers. The rollers 24 taper toward their outer ends, as clearly shown in Figures 2 and 3, and, therefore, as the rollers 24 rotate and the disk is turned, the marginal portion of the disk will be flattened in a direction to form a feathered edge. As the marginal edge of the disk is flattened, it may be shifted closer to the rollers to cause its marginal portion to extend between the rollers a greater distance and the lever may be actuated to impart greater pressure if found necessary. A portion of the liquid entering the cylinder 68 will move upwardly through the bore 71 to operate the gage 72 and by observing the gage, the operator of the machine can determine whether or not sufficient pressure has been applied. When a disk has been fully sharpened, pressure upon the bearing blocks must be relieved in order to permit the upper roller 24 to move away from the lower roller and allow the disk to be withdrawn from between the rollers. In order to accomplish this, it is merely necessary to open the valve 77 and liquid in the pipe 74 and cylinder 68 may then drain through the branch pipe 76 and back into the reservoir. It will thus be seen that this machine is so constructed that a disk such as used upon plows and harrows may be very easily rolled to restore a sharp edge and that heating of the disk will not be necessary and also it may be sharpened without grinding.

Having thus described the invention, what is claimed as new is:

1. A disk rolling machine comprising a frame, including corner posts, one corner post being hollow and constituting a reservoir for liquid, bearings carried by the corner posts and shiftable vertically, rollers having shafts journaled through the bearings, means for rotatably supporting a disk with a marginal portion of the disk engaged between the rollers, and means for imparting hydraulic pressure to the bearings for urging one roller toward the other including a pump for withdrawing liquid from the hollow corner post, and operating means for said pump.

2. A disk rolling machine comprising a frame, rollers at one side of said frame, bearings for said rollers shiftable vertically in said frame, means for rotatably supporting a disk and shifting the disk toward and away from the rollers, and means for applying hydraulic pressure for urging the bearings and rollers vertically toward each other including a vertically disposed liquid holding reservoir slidably engaged by certain of the bearings, a pump in said reservoir having a shaft projecting upwardly from the reservoir above the frame, and manually actuated means carried by said frame and engaged with the upper end of the pump shaft for operating the same.

3. A disk rolling machine comprising a frame including standards, one standard being hollow and constituting a liquid reservoir, bearings by said standards and shiftable vertically, rollers having shafts journaled through said bearings, a piston and cylinder in operative relation to one bearing, means for rotatably supporting a disk in

- position for disposing the marginal portion of the disk between the rollers, a pump for withdrawing liquid from said reservoir, an outlet pipe for said pump for delivering liquid into said cylinder, 5 a valve controlled branch for said pipe communicating with said reservoir, and means for operating said pump and forcing liquid through the pipe into said cylinder and urging one roller toward the other.
- 10 4. A disk rolling machine comprising a frame having upper and lower plates, corner posts between said plates, one post being hollow and constituting a liquid reservoir, bearings carried by companion posts and shiftable vertically, rollers having shafts journaled in said bearings, a cross beam above one bearing, a cylinder and a piston between the cross beam and last-mentioned bearing, a pump for withdrawing liquid from said reservoir, a pipe leading from said pump to 15 said cylinder having a valve controlled branch communicating with the reservoir below the cylinder, and means for operating said pump and forcing liquid through the pipe to the cylinder and exerting hydraulic pressure for forcing the 20 rollers into compressing engagement with the marginal portion of a disk disposed between the rollers.
- 25 5. A disk rolling machine comprising a frame having a base, posts rising from the base, a top supported by said posts, one post constituting a reservoir, bearings extending between companion posts and shiftable vertically, rollers having shafts journaled in said bearings, a cross beam carried by certain of said posts, a cylinder and piston disposed between the cross beam and a bearing under the same, means to rotatably support a disk in position to have its marginal portion engaged between the rollers, a pump in said 30 reservoir having a shaft extending upwardly from the reservoir above the cross beam, a service pipe leading from said pump to said cylinder and having a valve controlled branch communicating with the reservoir below the cylinder whereby liquid may drain from the cylinder into 35 the reservoir when the valve is open, and an operating lever pivotally connected with the cross beam and connected with the upper end of the pump shaft for operating the pump and forcing liquid to the cylinder and applying hydraulic pressure for forcing one roller toward 40 the other.
- 45 6. A disk rolling machine comprising a frame including a base plate, a top plate, posts extending between said plates, one post being hollow and constituting a liquid reservoir, sets of bearings extending between companion posts one above another, the bearings of one set being shiftable vertically, shafts journaled through said bearings, rollers carried by said shafts, means 50 for transmitting rotary motion from one shaft to another, a drive shaft rotatably supported upon the top plate, means for transmitting rotary motion from the drive shaft to the last-mentioned shaft, means for rotatably supporting a disk in position for engagement of its marginal portion between rollers, a cross beam disposed over the shiftable bearings in spaced relation to the upper one thereof, a cylinder and piston disposed between the cross beam and upper shiftable bearing, a pump in said reservoir having a pump shaft extending vertically and protruding from the upper end of the reservoir, a service pipe leading from said pump to said cylinder and having a valve controlled branch 60 communicating with the reservoir below the cylinder, a fulcrum carried by said cross beam, and an operating lever pivoted to the fulcrum and engaged with the upper end of the pump shaft.
- 65 7. A disk rolling machine comprising a frame, bearings shiftable vertically in said frame and disposed one above another, rollers having shafts journaled through said bearings, a piston and cylinder for operating against the upper bearing, a reservoir, a pump in the lower portion of said reservoir, a service pipe for delivering liquid from the pump to the cylinder and having a valve controlled branch communicating with the reservoir above the pump and below the cylinder whereby liquid may drain from the cylinder through the branch pipe back into the reservoir when the valve of the branch pipe is open, manually actuated means for operating said pump, and means for rotatably supporting a disk in position to have its marginal portion engaged between the rollers.
- 70 8. A disk rolling machine comprising a frame, bearings in the frame shiftable vertically therein and disposed one above another, rollers having shafts journaled through the bearings, means for rotating said rollers, means for applying pressure to the upper bearing and forcing one roller toward the other, a bar slidably carried by said frame with one end projecting therefrom, means to secure said bar in a longitudinally adjusted position, a bracket connected with the outer end portion of said bar for angular and transverse adjustment, a support carried by said bracket and vertically adjustable, and means carried by said support for rotatably mounting a disk with a marginal portion of the disk engaged between the rollers.
- 75 9. A disk rolling machine comprising a frame, rotatable rollers carried by said frame and disposed one above the other at a side of the frame, means for rotating said rollers, means for applying pressure and forcing one roller toward the other, a bar carried by said frame with one end portion projecting outwardly therefrom, the bar being shiftable longitudinally and adapted to be secured in a set position, a clamp carried by the outer end of said bar, a bracket carried by said clamp and extending transversely of the bar, a support having a standard engaged by the bracket and shiftable vertically therethrough to vertically adjust the support, and means for rotatably mounting a disk carried by the upper end of said support and shiftable toward and away from said rollers.
- 80 10. A disk rolling machine comprising a frame, rollers carried by said frame, means for exerting pressure and forcing one roller toward the other, a bar having one end portion projecting from said frame, bearing brackets carried by said frame for supporting the bar in a longitudinally adjusted position, a groove being formed in the bar, a disk carried by one bearing bracket and engaged in the groove to control longitudinal shifting of the bar and prevent rotation thereof, a clamp carried by the outer end of said bar, a bracket extending transversely of the bar and engaged by said clamp for angular adjustment of the bracket, a support carried by said bracket and shiftable vertically, and means carried by said support to rotatably mount a disk with a marginal portion of the disk disposed between said rollers.
- 85 11. A disk rolling machine comprising a frame, rollers carried by said frame, means for rotating said rollers, means for exerting pressure and forcing one roller toward the other, a bar pro-

jecting from said frame and adjustable longitudinally, a bracket carried by said frame for angular adjustment, a support having a table and a standard depending therefrom and carried by said bracket, a carriage upon said table and pivoted eccentric thereto, rotary members carried by said carriage, a post journaled through said carriage concentric thereto and projecting upwardly from the carriage, means

to secure a disk to be sharpened about the post in position to rest upon said rotary members with its marginal portion engaged between the rollers, means for moving said carriage about its pivot to shift the disk toward and away from the rollers, and means for securing the carriage in a set position. 5

LUTHER T. PEDIGO.
